US00D753114S

(12) **United States Design Patent**
Osterhout

(10) **Patent No.:** **US D753,114 S**
(45) **Date of Patent:** **** Apr. 5, 2016**

(54) **AIR MOUSE**(71) Applicant: **Osterhout Group, Inc.**, San Francisco, CA (US)(72) Inventor: **Ralph F. Osterhout**, San Francisco, CA (US)(73) Assignee: **Osterhout Group, Inc.**, San Francisco, CA (US)(**) Term: **14 Years**(21) Appl. No.: **29/513,677**(22) Filed: **Jan. 5, 2015**(51) LOC (10) Cl. **14-02**

(52) U.S. Cl.

USPC ..... **D14/402**(58) **Field of Classification Search**USPC D14/402-411, 356, 388, 389, 383-385,
D14/417, 426; 345/156-167; 463/36-38;

(57) **CLAIM**

The ornamental design for an air mouse, as shown and described.

DESCRIPTION

FIG. 1 is a top rear perspective view of an embodiment of the new design;

FIG. 2 is a front view thereof;

FIG. 3 is a side view thereof;

FIG. 4 is a side view thereof;

FIG. 5 is a bottom view thereof;

FIG. 6 is a rear view thereof; and,

FIG. 7 is a top view thereof.

The broken lines in FIGS. 1-7 are for environmental purposes only and form no part of the claimed design.

1 Claim, 4 Drawing Sheets
